UNITED STATES PATENT OFFICE.

SAMUEL HAGEMAN, OF CRYSTAL, MICHIGAN.

GAS-ENGINE.

1,244,490.

Specification of Letters Patent. Patented Oct. 30, 1917.

Application filed January 16, 1915. Serial No. 2,612.

To all whom it may concern:

Be it known that I, SAMUEL HAGEMAN, a citizen of the United States, residing at Crystal, in the county of Montcalm and State of Michigan, have invented certain new and useful Improvements in Gas-Engines, of which the following is a specification.

The invention purposes to enable the construction of an internal combustion engine utilizing a cylinder and reciprocating piston in which a working impulse may be imparted on every inward movement of the piston, but which will retain the advantages of the scavenging action of the usual four-cycle engine and of the suction stroke. A further object is to enable the construction of such an engine in compact form and to provide a novel construction of operative parts of a desirable character.

Additional objects and advantages and features of invention will appear from the construction, combination and arrangement of parts hereinafter set forth, and shown in the drawings, in which,

Figure 1 is a vertical sectional view of an engine embodying the principles of my invention,

Fig. 2 is a similar view thereof at the end of the working stroke,

Fig. 3 is a fragmentary vertical section at right angles to Fig. 1.

There is illustrated an engine including a crank case 10 and crank shaft 11 mounted therein of any suitable construction, the crank case having a cylinder 12 mounted thereon comprising a casting closed at the outer end, suitably cored to form a water jacket 13, and finished on the interior to receive the piston 14, the latter also being of a familiar type, and connected to the shaft by the usual connecting rod.

The cylinder is provided with an inlet port 15 immediately adjacent its head 16 with which suitable inlet connections 17 may be made. An exhaust port 18 is formed adjacent the lower limit of movement of the piston 14, in the side of the cylinder, and a spark plug 20 mounted at a suitable point in the cylinder. A second piston 19 is mounted slidably in the cylinder outwardly of the piston 14, with which reciprocating connections are made, extending through a suitable packing box 21 in the head 16, this connection comprising a stem 22, the outer end of which is connected to one end of an oscillating arm 23, pivoted upon a suitable

lug 24 on the cylinder head, sliding connection being made with the arm. A suitable spring 25 is confined between the arm and the cylinder head to hold the arm yieldably at the outer limit of its movement, whereby the piston is raised against the cylinder head. Extending transversely over this arm there is a cam shaft 26 revolvably mounted in suitable brackets 27 and 28, and having a cam 29 thereon arranged to bear upon the arm 23. This shaft is extended outwardly from the cylinder over the port 15, and is provided with a sprocket 30, engaged with which there is a chain 31 driven from the shaft 11, as shown. The shaft 26 should rotate synchronously with the crank shaft. A valve passage 33 is formed in the cylinder casting, extending across the port 15 and opening through the outer end of the casting beneath the shaft 26. A sliding valve 34 is mounted in this passage movable across the port 15 for closure thereof, and connected by a link 35 to a crank 36 thereover. This crank is disposed on a radius of the shaft 26 opposite the side on which the maximum radius of the cam 29 occurs, so that the valve opens when the piston moves downwardly and closes on its return.

The port 15 is of such dimensions on its inner side that it communicates with the space above the piston as soon as the latter begins to move downwardly and extends below the piston when the latter is at the upper limit of its movement, the valve 34 being suitably recessed to provide a clearance between the piston and valve.

In operation, with the parts arranged as shown in Fig. 1, a charge having been admitted, ignition is caused by any suitable means, and the crank shaft having a slight momentum, the piston 14 will be caused to move downwardly. The cam 29 is so shaped that the piston 19 will remain stationary until the piston 14 has completed a large part of its movement, when it will be rapidly moved downwardly, this movement being continued until the piston 14 has begun its return movement, with a resultant scavenging action. The piston 19 stops short of the piston 14 at the lower limit of its movement, although the extent of movement should be somewhat greater than illustrated in the drawings to attain the fullest efficiency. Upon outward movement of the piston 14 in the cylinder the piston 19 is returned to initial position with great ra-

pidity. During the downward movement of the piston 19, the valve 34 being open, the charge will be drawn into the cylinder over the piston, through the inlet port, and the 5 valve closes in time to prevent escape of the charge through the inlet port as the piston 19 rises. The recessed inner side of the valve 34 will allow passage of the gases to the inner side of the piston 19 after it rises 10 sufficiently.

What is claimed is:

In an engine of the character described, a headed cylinder having an inlet port adjacent the head and a by-pass recess in the 15 inner face of the cylinder in communication with the port and extending to the head, a

piston in the cylinder constructed to lie within the longitudinal limits of this by-pass recess at times, a working piston in the cylinder, means to reciprocate the first named 20 piston, a valve for said port slideable in said recess and across said port having an inner face spaced from the projected arc of the cylinder inner face, and operative connections between the valve and the working 25 piston for the purposes described.

In testimony whereof I have affixed my signature in presence of two witnesses.

SAMUEL HAGERMAN.
